UNITED STATES PATENT OFFICE.

JOHN ZANDER, OF CHICAGO, ILLINOIS.

REFRIGERATING APPARATUS.

1,415,504.

Specification of Letters Patent. Patented May 9, 1922.

Application filed May 17, 1916. Serial No. 98,038.

To all whom it may concern:

Be it known that I, JOHN ZANDER, a citizen of the United States, residing at Chicago, in the county of Cook and State of Illinois, have invented a new and useful Improvement in Refrigerating Apparatus, of which the following is a specification.

My invention relates, more particularly, to improvements in refrigerating apparatus of the type employing a generating chamber for gasifying, by heat applied thereto, a suitable refrigerating agent, such as ammonia, in solution, and a condensing chamber into which the ammonia-gas produced in the generator is discharged and reduced to a liquid condition, preparatory to its introduction into the refrigerating coils, and from which latter it passes in gaseous condition back into the solution in the generating chamber to replenish the ammonia-content thereof.

My primary object is to provide for the simplification of apparatus of this general character, to reduce the cost of construction thereof and the cost of operation; to provide for the automatic control of the heating means for the generator and the cooling medium for the condenser and the generator; and generally to provide improvements in apparatus of this character whereby they will be better adapted to perform the functions for which they are provided.

Referring to the accompanying drawings:

Fig. 1 is a view in elevation, partly diagrammatic, of an apparatus constructed in accordance with my invention; Fig. 2 is a view in longitudinal vertical sectional elevation of valve mechanism for controlling the supply of cooling medium to the generating and condensing chambers and the supply of the heating medium to the generator, the section being taken at the line 2 on Fig. 3 and viewed in the direction of the arrow; Fig. 3 is a section taken at the line 3 on Fig. 2 and viewed in the direction of the arrow; Fig. 4 is an enlarged section taken at the line 4 on Fig. 2 and viewed in the direction of the arrow, the valve proper of the construction being shown in the position it assumes when shifted from the position shown in Fig. 2 to the other position assumed by it in the operation of the apparatus; Fig. 5 is a plan view of the valve proper of Figs. 2, 3 and 4; Fig. 6 is a view in vertical elevation of a desirable form of valve for controlling the supply of heating medium to the generator; and Fig. 7, a similar view of one of the number of shut-off valves employed in the lines for the refrigerating agent.

The generating-chamber is represented at 8, this chamber, in the particular construction illustrated, being provided to receive the solution containing the refrigerating agent, such as ammonia, which is subjected to the necessary heat for gasifying the ammonia content thereof and driving it off under the desired pressure by any suitable means. The means shown for this purpose is gas, which is supplied to a burner 9 located below an opening 10 in a casing 11 partially enclosing the chamber 8, through a valve-controlled pipe leading from a suitable source of gas supply, as hereinafter explained. A pipe 12 leads from the upper end of the chamber 8 and connects with the upper end of a coil 13 located in a tank 14, the other end of this coil opening into a chamber 15 located in the bottom of this tank, the pipe 12 having interposed therein a check-valve 16 of any desirable construction, which permits of the passage of the ammonia gas from the chamber 8 into the coil 13, but prevents a reverse flow. The chamber 15 is provided for receiving the ammonia after it is condensed in the coil 13 and furnishes the supply of liquid refrigerant, which flows therefrom through a pipe 13^a to the expansion-valve, which may be of any suitable construction and is represented at 16, this valve opening into the refrigerating coil 17. The pipe 13^a extends downwardly at one end through the tank 14 and the top of the chamber 15 into the latter to a point close to the bottom thereof, as represented. The other end of the refrigerating-coil 17 is connected by a pipe 19 with a spray-ring 20 located in the lower portion of the generating-chamber 8, for conducting the spent ammonia gas, after performing its refrigerating function, into the solution in the chamber 8 for replenishing the supply of ammonia content thereof, the pipe 19 containing a check-valve, represented at 21, and which may be of any suitable construction, operating to

permit the flow of gas through the pipe 19 into the chamber 8, but preventing reverse flow.

Means are provided for maintaining the circulation of a cooling medium in the tank 14 during the operation of the generator, to properly condense the ammonia gases discharged into the coil 13; to supply a cooling medium to the coil 22 provided in the generating-chamber 8 during the periods when the generator is not operating as a generator; and to control the operation of the burner for the generator.

In accordance with the preferred illustrated embodiment of my invention, which employs water as the cooling medium and gas as the heating medium for the generator, provision is made for automatically shutting off the supply of gas to the burner 9 when the ammonia content of the solution in the generator 8 becomes so reduced by the generating action, that it is not commercially feasible to continue to generate gas from this solution until the ammonia content thereof has been replenished, under which conditions the chamber 15 becomes charged with the liquid refrigerant, automatically starting the circulation of cooling water through the coil 22, and automatically shutting off the supply of cooling water to the tank 14; and as soon as the supply of liquid refrigerant in the chamber 15 becomes reduced to a certain degree by the use thereof in the refrigerating-coil 17, for automatically starting the flow of cooling water through the tank 14, automatically discontinuing the flow of cooling water through the coil 22 of the generator, and automatically starting the burner 9 into operation to recharge the chamber 15 with liquefied ammonia, a description of the means provided for this purpose being as follows:

In carrying out this cycle of operations, I preferably provide the valve mechanism shown in Fig. 2, this valve comprising a casing 23 having a centrally-disposed chamber 24 containing a longitudinally-shiftable valve 25, and chambers 26 and 27 located at opposite ends of the chamber 24. The chamber 24 contains an opening 28 in its side wall, which communicates with the interior of a housing 29 which connects with a pipe 30 which would lead from any suitable source of relatively cold water supply, as, for example, the ordinary service main, and through which the water is supplied to the cooling means for the condensing part of the apparatus and the generator 8 alternately, through a pipe 31 which connects at one end with the lower end of the tank 14 and at its opposite end with a port 32 in a side wall of the chamber 24, and through a pipe 33 which connects at one end with the upper end of the coil 22 and at its opposite

end with a port 34 located in a side wall of the chamber 24, the upper end of the tank 14 being connected to a drain-pipe 35 which may lead to a sewer and the lower end of the coil 22 being connected with this drain-pipe through a pipe 36.

The valve 25 contains in its periphery and intermediate its ends an annular recess 37, the bottom of which is annularly restricted, as indicated at 38, to provide annular shoulders 39 on which a circular band 40 of screening material, as for example, very fine mesh, is seated to prevent solid matter from entering the chamber 24 at opposite ends of the valve. The parts of the valve structure are so constructed and arranged, as shown, that when the valve 25 is in one position (the position shown in Fig. 2) water can flow from the pipe 30 into the housing 29, thence through the port 28, to the groove 37, and out through the pipe 31 to the tank 14; and when the valve is shifted to the right in Fig. 2 to the position shown in Fig. 4, from the groove 37 into and through the port 34 and pipe 33 to maintain a flow of cold water through the coil 22, the arrangement being such that when the water supply is open to the pipe 31, it is closed to the pipe 33, and vice versa.

The end walls of the chamber 24 contain passages 41 and 42 which communicate with passages 43 and 44 provided in plugs 45 and 46 confined in openings in the said end walls, the inner ends of the passages 43 and 44 opening into the chamber 24 at opposite sides of the valve 25, respectively. The passage 43 is controlled by a valve 47 mounted on a rod 48 slideable in the plug 45 and having a head 49 between which and a tension-nut 50 surrounding and secured to the plug 45, a coiled spring 51 is interposed, this spring tending to close the valve 47. The chamber 26 contains a flexible diaphragm 52 against which the head 49 bears when the valve 47 is closed, this diaphragm being spaced a slight distance from the adjacent end wall of the chamber 26 to provide a space 53 into which a pipe 54 opens at one end, the opposite end of this pipe communicating with the interior of a tube 55 closed at its upper and lower ends and preferably containing water or any other suitable liquid, which gasifies at a higher temperature than that at which the refrigerating agent employed, gasifies, which rises to a point short of the connection of the pipes 54 and 55 with each other, the pipe 55 extending downwardly into the generating-chamber 8, preferably to a point close to the bottom of the latter, for a purpose hereinafter explained. Communication between the passage 44 and the chamber 24 is controlled by means of a valve 56, of the needle type, the point of the valve co-operating with a valve-seat formed on the inner end of a plug 57

screwed into the end of the passage 44 and containing an opening therethrough forming a continuation of the passage 44. The opposite end of the valve 56 is provided with a head 58 between which and a tension-nut 59 surrounding and secured to the plug 46, a coil-spring 60 extends, this spring tending to move the valve 56 to open condition. The chamber 27 contains a flexible diaphragm 61 against which the head 58 bears, this diaphragm being spaced a slight distance from the adjacent end wall of the chamber 27 to provide a space 62 into which one end of a pipe 63 opens, the opposite end of this pipe opening into the chamber 15 through the top of the latter.

The valve 25 contains passages 64 and 65 which communicate with, and lead in opposite directions from, the groove 37, the outer 20 ends of these passages communicating with the interior of the chamber 24 at opposite sides, respectively, of the valve 25, these passages being relatively small as compared with the passages that communicate with the opposite ends of the chamber 24 and are controlled by the valves 47 and 56, respectively.

The control of the supply of gas to the burner 9 through the pipe 66 connected therewith, and which in practice would be connected with any suitable source of gas supply, is effected through the water supply controlled by the valve 25, and to this end the gas-controlling valve represented at 67, 30 and interposed in the pipe 66, is connected with the pipe 31 by a pipe 68, to so operate the valve 67 that gas is supplied to the burner 9 during that part of the cycle of operation of the apparatus in which the cooling 35 water is supplied to the tank 14 and the supply thereto to the burner is shut off during that part of the cycle in which cooling water is supplied to the coil 22, the burner 9 being provided with a pilot connected with a pipe 45 69 which connects with the gas supply pipe 66 in advance of the valve 67 in order that the burner may be instantly lighted automatically upon opening the valve 67. A suitable form of the valve 67 is shown in 50 Fig. 6, this valve, generally stated, comprising a valve-casing 70 containing a chamber 71 into which the pipe 68 opens beneath a flexible diaphragm 72 in said chamber, this chamber being in communication with the 55 pipe 66, above the diaphragm 72, through the passages 73 and 74, respectively; and a reciprocable valve 75 mounted in the passage 74 for controlling the flow of gas through the passage 73 and thence to the burner. 60 The valve 75 co-operates at its section 76 with the seat 77 to close the valve which is backed up by a coil-spring 78 tending to move it to closed position, and co-operating with the valve is a slidable member 79 which 65 engages at its upper end the under surface

of the valve and engages at its lower end the diaphragm 72.

The operation of the apparatus is as follows: Assuming that the generating-chamber 8 is charged up to about the level indicated at X with an ammonia solution of about 30 per cent strength, as is commonly used, and that the valve-mechanism of Fig. 2 is in the position therein represented, water from the supply will pass through the pipe 30, valve-mechanism of Fig. 2, pipe 31, and thence through the tank 14 from which it overflows through the pipe 35 to the discharge, and will also fill the pipe 68 under pressure sufficient to unseat the valve 76, permitting gas to flow to the burner 9, where it burns, heating the liquor in the chamber 8. The subjection of the solution, as stated, to heat, gasifies the ammonia therein, which passes from this chamber 85 through the pipe 12 and into the coil 13, wherein it is subjected to the cooling action of the water entering the tank 14 from the pipe 31, and discharges into the chamber 15 in liquid condition. The generator continues 90 to operate to gasify the ammonia-content of the solution therein, until the ammonia-content becomes reduced to a predetermined degree, whereupon the pressure generated by the vapor in the closed pipe 55, acting 95 against the diaphragm 52 of the valve mechanism, in opposition to the action of the spring 51, unseats the valve 47 which causes the water-pressure exerted against the right-hand end of the piston-valve 25 in 100 Fig. 2 to become reduced as compared with the pressure against it at its opposite end, and thus this valve shifts to the right in Fig. 2 to its extreme position, in which it is moved out of registration with the pipe 31 and into registration with the pipe 33, the water displaced in this operation discharging through the passages 43 and 41 and pipe 80 which communicates with a pipe 81 discharging preferably into the tank 14. 105 The actuation of the valve 25, as stated, arrests the flow of cooling medium to the tank 14 through the pipe 31 and reduces the pressure in the pipe 68 to such a degree that the valve 75 automatically closes under the action of its spring 78, which shuts off the supply of gas to the burner 9. At the same time, the valve upon moving to the position stated opens the pipe 33 to the water supply with which this valve mechanism is 110 connected, whereupon the coil 22 is supplied with the desired cooling medium, which serves to cool the ammonia solution in the generator 8 upon extinguishing the burner 9 to reduce the pressure in the generator and 115 to absorb the heat produced by the intermixing of the ammonia gas, flowing from the refrigerating-coil 17, with the solution in the generator 8 during the refrigerating 120 operation hereinafter referred to. 125 130

The liquid refrigerant passes from the chamber 15 through the pipe 13^a and expansion-valve 16 into the refrigerating-coil 17, under the pressure in the chamber 15, 5 to perform the refrigerating function in this coil, the ammonia gas passing from the latter through the pipe 19 to the spray-ring 20 from which it discharges into the ammonia solution in the chamber 8 to replenish the 10 ammonia content thereof, the cooling of the contents of the chamber 8, as stated, maintaining the flow of ammonia gas into the solution in the tank 8 for intermixture therewith.

15. When the supply of liquid refrigerant in the chamber 15 becomes so reduced that the pressure in this chamber drops below a predetermined degree, the pressure exerted against the diaphragm 61 through the pipe 20 e3 and in opposition to the spring 60, and which pressure is sufficient to maintain the valve 56 in closed condition during the operation of the generator, becomes reduced to such a degree that the spring 60 opens the 25 valve 56, permitting the water in the chamber 24 at the left-hand side of the valve 25 in Fig. 2, to readily escape therefrom through the passages 44 and 42 and a pipe 82 which discharges into the pipe 81, the 30 valve 47 having previously automatically closed by the reduction of pressure in the pipe 55 upon extinguishing the burner 9, thus reducing the pressure at this side of the valve 25 which causes it to slide to the 35 position represented in Fig. 2, in which the pipe 33 is cut off from the water supply and the pipe 81 is opened thereto, thus causing the circulation of cooling water through the coil 22 to cease, restoring the circulation of 40 the cooling water through the tank 14, and, by reason of the pressure in the pipe 68, opening the valve 67 to supply gas to the burner 9, where it is automatically ignited by the pilot, and the operations hereinbefore 45 referred to are repeated until the supply of liquid refrigerant in the chamber 15 is replenished, whereupon the other described operations are resumed, these operations alternating under the automatic control of the 50 described apparatus provided for this purpose.

It is desirable, as, for example, when repairs are to be made, that provision be made for shutting off certain portions of the lines 55 through which the refrigerating agent flows, and to this end the various pipes traversed by the refrigerating agent are equipped with valves which are preferably located in the pipes 12, 18, 19 and 63, and are represented 60 at 83. These valves may be of any suitable form but preferably are of the form shown in Fig. 7, each comprising a casing 84 containing a chamber 85 communicating with the inlet and outlet of the casing. The casing 65 contains a needle valve 86 which co-

operates with a seat 87, and is equipped with a removable cap 88 which covers that portion of the valve 86 which is provided for co-operation with a wrench or other tool for adjusting the valve.

It is sometimes desirable that the valve 25 be shifted by hand, and this is provided for by mounting, on a shaft 89 journaled in the housing 29 and provided with an operating hand-wheel 90, an arm 91 which extends through the slot 28 and into the peripheral groove 37 of the valve, thus providing an engagement between these parts whereby the valve may be shifted by hand, if desired.

To avoid the escape of ammonia fumes into the room in which the apparatus is located, should the diaphragm 61 become impaired or the pressure in the chamber 8 become sufficiently great to open the relief-valve 92 for this chamber, I connect the interior of the chamber 27 with the pipe 81, by a pipe 93, and the discharge of relief-valve 92, with a pipe 94 which opens into pipe 81, thus leading the fumes into the water 90 in the tank 14 wherein they become absorbed.

It will be noted from the foregoing that by providing for the actuation of the fluid-pressure-operated valve, in one direction, by the pressure of vapor generated by the heat 95 of the generating means, the operation of the apparatus is rendered dependable inasmuch as the pressure exerted by saturated vapor at any given temperature is fixed and is not dependable upon any given quantity of 100 liquid.

The provision of the shell 11 surrounding the chamber 8 and spaced therefrom but reaching short of the upper end of this chamber is desirable, inasmuch as it serves to 105 effect the desired heating of the solution in the tank 8 by operating the burner 9 and leaves the upper end of the chamber 8, through which the gasified refrigerating agent passes in its passage to the coil 13, 110 exposed to the cooling effect of the surrounding atmosphere, thus acting as a rectifier or dehydrator to precipitate water-vapors in the gas.

While I have illustrated and described a 115 particular embodiment of my invention, I do not wish to be understood as intending to limit it thereto, as the same may be variously modified and altered without departing from the spirit of my invention.

What I claim as new and desire to secure by Letters Patent is:—

1. In refrigerating apparatus, the combination of generating means for gasifying a refrigerating agent in solution, condensing means for the gasified refrigerating agent in communication with said generating means, a refrigerating coil in communication with said generating means and said condensing means, means for supplying heat to said 125 130

generating means, and means operated by fluid-pressure, operating automatically, to control said last-named means to discontinue the supplying of heat to said generating means when the solution containing the refrigerating agent becomes weakened to a predetermined degree.

2. In refrigerating apparatus, the combination of generating means for gasifying a refrigerating agent in solution, condensing means for the gasified refrigerating agent in communication with said generating means, a refrigerating coil in communication with said generating means and said condensing means, means for supplying heat to said generating means, means for supplying a cooling medium to said condensing means, and means operated by fluid-pressure, operating automatically, to control said means for supplying heat to said generating means and said means for supplying a cooling medium to said condensing means, to discontinue the supplying of heat to said generating means, and the cooling medium to said condensing means.

3. In refrigerating apparatus, the combination of generating means for gasifying a refrigerating agent in solution, condensing means for the gasified refrigerating agent in communication with said generating means, a refrigerating coil in communication with said generating means and said condensing means, means for supplying heat to said generating means, means for supplying a cooling medium to said condensing means, and means operated by fluid-pressure, operating automatically, to control said means for supplying heat to said generating means and said means for supplying a cooling medium to said condensing means, to discontinue the supplying of heat to said generating means and the cooling medium to said condensing means when the solution containing the refrigerating agent becomes weakened to a predetermined degree.

4. In a refrigerating apparatus, the combination of generating means for gasifying a refrigerating agent in solution, condensing means for the gasified refrigerating agent in communication with said generating means, a refrigerating coil in communication with said generating means and said condensing means, means for supplying heat to said generating means, means for supplying a cooling medium to said condensing means, means for supplying a cooling medium to said generating means, means operated by fluid-pressure, operating automatically, to control said means for supplying heat to said generating means and said means for supplying a cooling medium to said condensing means, to discontinue the supplying of heat to said generating means and the cooling medium to said condensing means, and fluid-pressure-operated means, operat-

ing automatically, to discontinue the supplying of cooling medium to said generating means.

5. In refrigerating apparatus, the combination of generating means for gasifying a refrigerating agent in solution, condensing means for the gasified refrigerating agent in communication with said generating means, a refrigerating coil in communication with said generating means and said condensing means, means for supplying heat to said generating means, means for supplying a cooling medium to said condensing means, means for supplying a cooling medium to said generating means, and means operated by fluid-pressure, operating automatically, to discontinue the supplying of cooling medium to said condensing means and the supplying of heat to said generating means and to supply a cooling medium to said generating means, when the solution containing the refrigerating agent becomes weakened to a predetermined degree, and to discontinue the supplying of cooling medium to said generating means and to supply cooling medium to said condensing means and heat to said generating chamber when the supply of liquefied refrigerating agent becomes reduced to a predetermined extent.

6. In refrigerating apparatus, the combination of generating means for gasifying a refrigerating agent in solution, condensing means for the gasified refrigerating agent in communication with said generating means, a refrigerating coil in communication with said generating means and said condensing means, means for supplying heat to said generating means, a conduit adapted to convey a cooling medium under pressure to said condensing means, and valve-mechanism operated by said cooling medium, operating automatically, to discontinue the supplying of heat to said generating means and cooling medium to said condensing means when the solution containing the refrigerating agent becomes weakened to a predetermined degree.

7. In refrigerating apparatus, the combination of generating means for gasifying a refrigerating agent in solution, condensing means for the gasified refrigerating agent in communication with said generating means, means for supplying heat to said generating means, a container for a fluid positioned to be subjected to the heat supplied to the generating means, a source of fluid pressure, controlling means for said heat-supplying means operated by fluid pressure from said supply, valve mechanism controlling the flow of fluid to said last-named means, and means, controllable by the pressure of vapor generated in said container, for controlling the operation of said valve mechanism.

8. In refrigerating apparatus, the combination of generating means for gasifying a

- refrigerating agent in solution, condensing means for the gasified refrigerating agent in communication with said generating means, means for supplying heat to said generating means, a container for a fluid positioned to be subjected to the heat supplied to the generating means, means for supplying a cooling medium to said condensing means, and means, controllable by the pressure generated in said container, for controlling the operation of said means for supplying heat to said generating means and a cooling medium to said condensing means.
9. In refrigerating apparatus, the combination of generating means for gasifying a refrigerating agent in solution, condensing means for the gasified refrigerating agent in communication with said generating means, means for supplying heat to said generating means, a container for a fluid positioned to be subjected to the heat supplied to the generating means, means for supplying a cooling medium to said condensing means, and fluid-pressure-operated means, controllable by the pressure generated in said container, for controlling the operation of said means for supplying heat to said generating means, and a cooling medium to said condensing means.
10. In refrigerating apparatus, the combination of generating means for gasifying a refrigerating agent in solution, condensing means for the gasified refrigerating agent in communication with said generating means, means for supplying heat to said generating means, fluid-pressure-operated valve mechanism, means controlled by said valve mechanism for controlling said means for supplying heat to said generating means, and means, operating automatically, when the solution containing the refrigerating agent becomes weakened to a predetermined degree, to operate said mechanism and to discontinue the supply of heat to said generating means, and when the supply of liquefied refrigerating agent becomes reduced to a predetermined extent to operate said valve to a position in which heat is supplied to said generating means.
11. In refrigerating apparatus, the combination of generating means for gasifying a refrigerating agent in solution, condensing means for the gasified refrigerating agent in communication with said generating means, a refrigerating coil in communication with said generating means and said condensing means, means for supplying heat to said generating means, means for supplying a cooling medium to said condensing means, means for supplying a cooling medium to said generating means, valve mechanism operating when in one position to supply gas to said generating means and cooling medium to said condensing means and arrest the flow of cooling medium to said generating means, and when in another position to cause the supplying of heat to said generating means and cooling medium to said condensing means to be discontinued and supply cooling medium to said generating means, means controlled by a change in condition in said generating means, for controlling the movement of said valve in one direction, and means controlled by a change of condition in said condensing means for controlling the movement of the valve in the opposite direction.
12. In refrigerating apparatus, the combination of generating means for gasifying a refrigerating agent in solution, condensing means for the gasified refrigerating agent in communication with said generating means, a refrigerating coil in communication with said generating means and said condensing means, means for supplying heat to said generating means, means for supplying a cooling medium to said condensing means, means for supplying a cooling medium to said generating means, valve mechanism operating when in one position to supply gas to said generating means and cooling medium to said condensing means and arrest the flow of cooling medium to said generating means, and when in another position to cause the supplying of heat to said generating means and cooling medium to said condensing means to be discontinued and supply cooling medium to said generating means, means controlled by a change in condition in said generating means, for controlling the movement of said valve in one direction, and means controlled by a change of condition in said condensing means for controlling the movement of the valve in the opposite direction.
13. In refrigerating apparatus, the combination of generating means for gasifying a refrigerating agent in solution, condensing means for the gasified refrigerating agent in communication with said generating means, a refrigerating coil in communication with said generating means and said condensing means, means for supplying heat to said generating means, means for supplying a cooling medium to said condensing means, means for supplying a cooling medium to said generating means, valve mechanism operating when in one position to supply gas to said generating means and cooling medium to said condensing means and arrest the flow of cooling medium to said generating means, and when in another position to cause the supplying of heat to said generating means and cooling medium to said condensing means to be discontinued and supply cooling medium to said generating means, said valve mechanism including a chamber, and a valve movable in said chamber, with passages communicating with said chamber at opposite ends thereof and opening into

- the supply of fluid pressure, means for relieving said valve-chamber at one end of said piston of the pressure therein, controllable by a change of condition in said generating means, and means for relieving said valve-chamber at its opposite end of the pressure therein contained controllable by a change of condition in said condensing means.
- 10 14. In refrigerating apparatus, the combination of generating means for gasifying a refrigerating agent in solution, condensing means for the gasified refrigerating agent in communication with said generating means, a refrigerating coil in communication with said generating means and said condensing means, a valve-casing containing a chamber having a port adapted to communicate with a source of fluid pressure, 20 and other ports, a valve in said chamber and shiftable therein, said valve containing passages whereby fluid-pressure from said source enters said chamber into its opposite ends, said valve operating to alternately 25 open said other ports in said valve-casing, means communicating with one of said other ports for conveying a cooling medium to said condensing means, means controlled by the pressure flowing through said last-referred-to port for supplying a heating medium to said generating means, means connected with the other of said other ports for conducting a cooling medium to said generating means, valve equipped ports at 30 the opposite ends of said chamber for venting the ends of this chamber alternately, means controlled by a change of conditions in said generating means for controlling the valve means for one end of said chamber, 35 and means controlled by a change of conditions in the condensing means for controlling the valve at the opposite end of said chamber.
- 15 15. In refrigerating apparatus, the combination of generating means for gasifying a refrigerating agent in solution, condensing means for the gasified refrigerating agent in communication with said generating means, a refrigerating coil in communication with said generating means and said condensing means, a valve-casing containing a chamber having a port adapted to communicate with a source of fluid pressure, and other ports, a valve in said chamber and 50 shiftable therein, said valve containing passages whereby fluid pressure from said source enters said chamber into its opposite ends, said valve operating to alternately open said other ports in said valve-casing, 55 means communicating with one of said other ports for conveying a cooling medium to said condensing means, means controlled by the pressure flowing through said last-referred-to port for supplying a heating medium to said generating means, means 60 65
- communicating with the other of said other ports for conducting a cooling medium to said generating means, said chamber containing relatively large passages opening into its opposite ends, a valve tending normally to seat, controlling one of said passages, a valve tending normally to become unseated, controlling the other of said passages, means operated by a change of conditions in said generating means for opening 70 one of said valves which tends to seat, and means controlled by a change of conditions in said condensing means for holding to its seat the one of the valves which tends to unseat.
16. In refrigerating apparatus, the combination of generating means for gasifying a refrigerating agent in solution, condensing means for the gasified refrigerating agent in communication with said generating means, means for supplying heat to said generating means, a fluid-pressure-operated valve, means controlled by said valve for controlling the supply of heat to said generating means, and means for controlling the position of said valve responsive to the increase in the heat of the said solution in the operation of gasifying the refrigerating agent contained in the solution.
17. In refrigerating apparatus, the combination of generating means for gasifying a refrigerating agent in solution, condensing means for the gasified refrigerating agent in communication with said generating means, means for supplying heat to said generating means, a fluid-pressure-operated valve mechanism for controlling said means for supplying heat to said generating means, comprising a casing containing a chamber communicating through a port 105 with a supply of fluid pressure, a valve in said chamber containing a passage communicating through said port with said supply and opening through the ends of said valve, means operating when said valve is in one position to cause said heat-supplying means to supply heat to said generating means and when said valve is in another position to discontinue the supplying of heat to said generating means, vent passages in 110 said valve-chamber at opposite ends of said valve and of greater cross-sectional area than the passage in said valve, valves controlling the passages in said valve-chamber, and means subjected to the heat applied to 115 said generating means for controlling one of said last-named valves to cause one end of said valve-chamber to become vented and permit said first-named valve to be moved by said fluid pressure to a position in which 120 the supply of heat to said generating means is discontinued when the solution containing the refrigerating agent becomes weakened to a predetermined degree, and means controlling the other of said last-named 125 130

valves to vent the other end of said valve-chamber to permit the fluid-pressure to shift said first-named valve to a position in which heat will be supplied to said generating means, when the supply of liquefied refrigerating agent becomes reduced to a predetermined extent.

18. The combination with a source of fluid under pressure, of a casing containing a chamber having a port in its side wall, a longitudinally-shiftable member in said chamber containing a passage open at all times to said supply of fluid-pressure and opening through opposite ends of said member, said chamber containing passages at its opposite ends of relatively greater cross-section than the passages in said member, and valves controlling the passages in the ends of said chamber.

19. The combination with a source of fluid under pressure, of a casing containing a chamber having a port in its side wall, a longitudinally-shiftable member in said chamber containing a passage open at all times to said supply of fluid pressure and opening through opposite ends of said member, said chamber containing passages at its opposite ends of relatively greater cross-section than the passages in said member, valves controlling the passages in the ends of said chamber, means tending to seat one of said last-named valves, means tending to unseat the other of said last-named valves, means for unseating the one of said valves which tends to seat, and means for seating the other of said valves which tends to unseat.

20. The combination with a source of fluid under pressure, of a casing containing a chamber having a port in its side wall, a longitudinally-shiftable member in said chamber containing a passage open at all times to said supply of fluid pressure and opening through opposite ends of said member, said chamber containing passages at its opposite ends of relatively greater cross-section than the passage in said member, valves controlling the passages in the ends of said chamber, means tending to seat one of said last-named valves, means tending to unseat the other of said last-named valves, diaphragms co-operating with said last-named valves for unseating and seating them, respectively, and means for supplying pressure against said diaphragm to actuate said last-named valves.

21. The combination with a source of fluid under pressure, of a casing containing a chamber having a port in its side wall, a longitudinally-shiftable member in said chamber containing a passage open at all times to said supply of fluid pressure and opening through opposite ends of said member, said chamber containing passages at its opposite ends of relatively greater cross-

section than the passage in said valve, and valves controlling the passages in the ends of said chamber, said chamber containing a port for connection with a pipe and said member containing a passage adapted to communicate with said last-named port when said member is in one position for discharging through said last-named port the fluid pressure introduced into said member and to be out of communication with said port when said member is moved to another position.

22. In refrigerating apparatus, the combination of generating means for gasifying a refrigerating agent in solution, condensing means for the gasified refrigerating agent in communication with said generating means, a refrigerating coil in communication with said generating means and said condensing means, means for conducting a cooling medium to said condensing means and heat to said generating means, valve mechanism for controlling the supplying of a cooling medium to said condensing means and heat to said generating means, and a plurality of means operating alternately by variance in conditions in said condensing means and said generating means to actuate said valve mechanism, for the purpose set forth.

23. In refrigerating apparatus, the combination of generating means for gasifying a refrigerating agent in solution, condensing means for the gasified refrigerating agent in communication with said generating means, means for supplying heat to said generating means, means for operating by fluid-pressure for controlling the operation of said means for supplying heat to said generating means, and vapor-generating means subject to the heat of said generating means and operating to control said last-named means by the vapor evolved by the heat of said generating means.

24. In refrigerating apparatus, the combination of generating means for gasifying a refrigerating agent in solution, condensing means for the gasified refrigerating agent in communication with said generating means, means for supplying heat to said generating means, means for supplying a cooling medium to said condensing means, means operated by fluid-pressure for controlling the operation of said means for supplying heat to said generating means, and said means for supplying a cooling medium to said condensing means, and vapor-generating means subject to the heat of said generating means and operating to control said fluid-pressure-operated means by the vapor evolved by the heat of said generating means.

25. In refrigerating apparatus, the combination of generating means for gasifying a refrigerating agent in solution, condensing means for the gasified refrigerating agent

- in communication with said generating means, means for supplying heat to said generating means, means for supplying a cooling medium to said condensing means, 5 means for supplying a cooling medium to said generating means, means operated by fluid-pressure for controlling the operation of said means for supplying heat, said means for supplying a cooling medium to the condensing means and said means for supplying water to said generating means, vapor-generating means subject to the heat of said generating means and operating, by the vapor evolved by the heat of said generating means to control the operation of said last-named means, for discontinuing the supply of heat to said generating means and a cooling medium to said condensing means and supplying a cooling medium to said 10 generating means, when the refrigerating-agent content of said generator becomes reduced below a predetermined degree.
26. In refrigerating apparatus, the combination of generating means for gasifying a refrigerating agent in solution, condensing means for the gasified refrigerating agent in communication with said generating means, means for supplying heat to said generating means, means operated by fluid-pressure for controlling said last-named means, and means controlled by the change in temperature in said generating means for controlling said last-named means to effect the discontinuation of the supply of heat to 25 said generating means when the solution containing said refrigerating agent becomes weakened to a predetermined degree.
27. In a refrigerating apparatus, the combination of generating means for gasifying a refrigerating agent in solution, condensing means for the gasified refrigerating agent in communication with said generating means, means for supplying heat to said generating means, fluid - pressure - operated means for 30 controlling the operation of said heat-supplying means, and means controllable by the pressure of vapor generated by the heat of the contents of said generating means, for controlling the operation of said last-named means.
28. In a refrigerating apparatus, the combination of generating means for gasifying a refrigerating agent in solution, condensing means for the gasified refrigerating agent in communication with said generating means, means for supplying heat to said generating means, means for supplying a cooling medium to said condensing means, fluid - pressure - operated means for controlling said heat-supplying means and said means for supplying a cooling medium to said condensing means, and means controllable by the pressure of vapor generated by the heat of the contents of said generating 35 means, for controlling the operation of said last-named means.
29. In a refrigerating apparatus, the combination of generating means for gasifying a refrigerating agent in solution, condensing means for the gasified refrigerating agent in communication with said generating means, means for supplying heat to said generating means, means for supplying a cooling medium to said condensing means, means for supplying a cooling medium to said generating means, and a plurality of means one of which is controllable by the pressure of vapor generated by the heat of the contents of said generating means and the other of which is controllable by the pressure of the condensed refrigerating fluid, for controlling the flow of cooling mediums to said condensing means and generating means, and the supplying of heat to said generating means, to effect the discontinuing of the supply of cooling medium to said condensing means and heat to said generating means and the supplying of a cooling medium to said generating means when the refrigerating agent content of said generating means becomes reduced to a predetermined degree, and to effect the discontinuing of the supply of cooling medium to said generating means and supply a cooling medium to said condensing means and heat to said generating means when the pressure of the fluid-refrigerating agent becomes reduced to a predetermined degree.
30. In refrigerating apparatus, the combination of generating means for gasifying a refrigerating agent in solution, condensing means for the gasified refrigerating agent in communication with said generating means, a refrigerating coil in communication with said generating means and said condensing means, means for supplying a cooling agent to said condensing means, means for supplying heat to said generating means operated by the flow of cooling agent to said condensing means to supply heat to said generating means during the flow of cooling agent to said condensing means, and automatically discontinue the supplying of heat to said generating means when the flow of cooling agent becomes reduced below a predetermined degree, and means automatically controlling the flow of cooling agent to said condensing means.
31. In refrigerating apparatus, the combination of generating means for gasifying a refrigerating agent in solution, condensing means for the gasified refrigerating agent in communication with said generating means, a refrigerating coil in communication with said generating means and said condensing means, means for supplying heat to said generating means, means operated by fluid-pressure for controlling said third-

named means to discontinue the supplying of heat to said generating means, a source of fluid-pressure, a conduit leading from said source of fluid-pressure to said condensing means and to said last-named means, and valve mechanism controllable by conditions in said generating means for controlling the flow of fluid-pressure through said conduit.

32. In refrigerating apparatus, the combination of generating means for gasifying a refrigerating agent in solution, condensing means for the gasified refrigerating agent in communication with said generating means, a refrigerating coil in communication

with said generating means and said condensing means, a source of fluid-pressure, means for supplying heat to said generating means and means operated by fluid pressure from said source operating automatically under such fluid-pressure to cause said third-named means to be in condition for supplying heat to said generating means and upon reducing the pressure against said last-named means to cause said third-named means to be in condition for discontinuing the supplying of heat to said generating means.

JOHN ZANDER.
